AGITATOR

Lewis A. James, Independence, Kans., assignor to
 The James Washer Company, Inc., Independence,
 Kans., a corporation of Kansas

Application April 1, 1938, Serial No. 199,423

7 Claims. (Cl. 68—131)

This invention relates to washing machines and more particularly to an oscillating agitator therefor of a type consisting of a bar movable in close proximity to the bottom of the tub.

5 In machines of this type, the clothes or other articles work under the agitator and become caught. The clothes when thus caught are subject to wear and tear and may become so wedged that they often entirely block movement of the 10 agitator. Foreign objects, such as nails and the like, which have not been removed from the pockets of the garments are also apt to get under the agitator and interfere with its operation.

15 It is, therefore, the principal objects of the present invention to provide an agitator of this character which is constructed to reduce tendency of the clothes and foreign objects to work thereunder; and to provide an agitator with flexible wings or flanges that are yieldable to prevent wedging of objects such as nails and the like that might accidentally find their way into the washer.

20 Further objects of the invention are to provide an agitator with a blade or paddle extending at substantially right angles to the directional movement thereof; to provide the agitator with means for supporting the flexible wings from scraping contact with the bottom of the tub; to provide an agitator constructed to form a pocket thereunder for trapping foreign objects; and to provide the wings of the agitator with perforations so that washing fluid is flushed through the pocket.

25 In accomplishing these and other objects of the invention, as hereinafter pointed out, I have provided improved details of structure, the preferred form of which is illustrated in the accompanying drawing, wherein:

30 Fig. 1 is a cross-section through a washing machine equipped with an agitator embodying the features of the present invention.

Fig. 2 is a perspective view of the agitator.

35 Fig. 3 is a cross-section through the agitator, particularly illustrating support of the flexible wings which form a part of the agitator bar.

40 Fig. 4 is a longitudinal section through one end of the agitator.

Referring more in detail to the drawing:

45 1 designates a washing machine which includes a tub 2, having a substantially semicylindrical bottom 3 terminating in upwardly extending side walls 4 and 5 that are connected by end walls 6 to form a washing chamber 7 for containing a washing solution 8. The top of the tub has an

opening 9 but is normally closed by a cover 10 seated upon an inset flange 11 extending inwardly about the perimeter of the tub as shown in Fig. 1. The tube as thus described is supported on the usual legs 12.

5 Mounted within the washing chamber is an agitator 13 that is constructed in accordance with the present invention to include a bar or blade portion 14 extending longitudinally of the semi-cylindrical bottom and which has its ends supported by arms 15 and 16. The arms 15 and 16 are preferably formed of flexible, slightly spring-like material and have outwardly extending collars 17 and 18 for shafts 19 that are oscillatably mounted in bearings 20 at the respective ends 10 of the tub, the arms being of sufficient length so that the blade portion of the agitator swings about the longitudinal axis of the tub and with their free ends slightly clearing the surface of the cylindrical bottom 3. The free ends of the 15 arms terminate in inwardly extending flanges 21 and 22 for forming stop shoulders arranged to support the ends of the flexible wings of the agitator blade so that it may not be sprung down by excess weight of clothes and not allowed to 20 come in contact with the bottom of the tub, as now to be described.

25 The bar portion 14 of the agitator includes a T member 23, having a head flange 24 and a centrally arranged web 25, as best shown in Fig. 3. Fixed to the ends of the T bar are plates 27 that are connected with the arms 15 and 16 by fastening devices, such as rivets or the like 30 29 to support the head flange of the T bar in upwardly spaced parallel relation with the 35 flanges 21 and 22, and the web 25 in a plane passing through the axis of the shafts 19. The arms 15 and 16 are thus rigidly connected by the T bar but are adapted to yield to and from the end walls of the tub by reason of the flexible 40 material from which they are constructed. The web 25 forms an agitator blade for producing oscillating currents in the washing solution and to act as an elevator for alternately moving the clothes across the bottom of the tub and up 45 the side walls thereof incidental to oscillation of the agitator.

50 Fixed to the flange head 24 is a sheet metal member 30, having a flat, central portion 31 conforming in width to the head and which is secured thereto by fastening devices, such as screws 32. The member 30 also includes flexible wings 33 and 34 terminating in lips 35 and 36 that are arranged so that the ends thereof seat directly upon the ends of the stop flanges 21 and 22. The 55

lips are thus supported from being pressed by the clothes against the bottom of the tub, but the wings are adapted to yield away from the bottom of the tub in case clothes or foreign objects tend 5 to wedge thereunder. In order to stiffen the lips 33 and 34, the edges thereof are bent retractively to provide a double thickness, as indicated at 37 and 38 and to present a smoothly rounded edge for contacting the articles being washed. The 10 wings 33 and 34 are sufficiently rigid to maintain contact of the lips with their supporting flanges 21 and 22. The wings 33 and 34 are preferably provided with a series of openings 40 and 41, through which the washing solution is adapted 15 to jet and for flushing the pocket 42 that is formed between the wings 33 and 34 and the tub bottom.

When the agitator is used on a power washer, one of the shafts 19 will be rigidly attached to 20 its collar and the outer end thereof will be provided with a suitable actuator mechanism, such as a lever 43 or other means. In the case of a hand machine, other connections might be provided for effecting oscillation of the agitator 25 without departing from the spirit of the invention.

In operating a washer equipped with an agitator constructed in accordance with the present invention, a suitable quantity of wash liquid is 20 poured into the tub and the clothes or other articles are immersed in the solution. The agitator is then oscillated so that the bar portion thereof swings back and forth across the bottom of the tub, alternately propelling the clothes up one 35 side wall and then the other. The clothes, upon being pushed up one side wall, drop back through the washing solution at the bottom of the tub and are then pushed by the agitator up the other side wall when it reverses its direction of movement. The clothes are thus in effect scooped 40 from off the bottom of the tub during their movement by the agitator and any part thereof that might slip under the flexible lip on the side in the direction of movement cannot progress far 45 enough thereunder to pass the opposite side by the time the agitator has reached the limit of its stroke. When the agitator approaches the top of its stroke that lip is carried away from the vertical wall portion of the tub so that the 50 clothes are released to drop back over the agitator portion of the blade into the bottom of the tub. The clothes are, therefore, kept free and in a constant state of agitation and thoroughly circulated in the washing solution.

55 Should a button engage under one of the lips of the agitator as it is moving forwardly up a wall of the tub, the flexible lip will yield sufficiently to prevent pressure on the bottom of the tub that might tend to wear the garment. Usually this yielding tendency is sufficient, aided by resistance of the clothes, to allow withdrawal of the caught object, however, as soon as the agitator reaches the top of its stroke, the button or the like is ordinarily withdrawn as the space 60 under the lip widens relatively to the side wall of the tub. Should a foreign object, such as a nail, engage under the agitator, with the agitator moving to the left, Fig. 1, the flexible wing yields upwardly so that it is impossible for the nail to 65 wedge thereunder and when the agitator reaches the top of its stroke the nail is loosened sufficiently so that it will drop into the pocket formed under the agitator, as shown at 42, Fig. 1. The nail or the like will thus be freely retained in 70 the pocket until removed, and is prevented from

damaging the article being washed, or the machine, as would be the case if the nail wedged under the agitator to resist its movement.

From the foregoing it is obvious that buttons, 5 buckles and the like fixed to the clothes, or foreign objects, cannot wedge under the agitator since they are readily releasable by reason of the flexible wings. It is also obvious that the flexible wings are supported from scraping contact with the bottom of the tub by means of the stop 10 flanges 21 and 22 on the arms 15 and 16. Should a garment tend to wedge between an end wall of the tub and one of the arms 15 or 16, the garment will cause lateral shifting movement of the agitator away from the wall of the tub a sufficient 15 distance to allow freedom of the garment. After the garment is freed the spring-like, flexible material of the arms will return the agitator to its central oscillatory position within the tub.

Attention is also directed to the fact that the 20 openings in the agitator wings not only create a jetting action of the washing solution, but they also provide for flushing of the pocket under the agitator to keep it in sanitary condition.

What I claim and desire to secure by Letters 25 Patent is:

1. In a washing machine, a tub having a substantially semicylindrical bottom, an agitator including a bar, arms fixed to the ends of the bar and having inwardly extending stops spaced below the bar, flexible agitator wings fixed to the bar and having portions engaging the stops, and means mounting the arms for oscillation about the axis of said semicylindrical bottom with the flexible wings in slightly spaced relation with said 35 bottom.

2. In a washing machine, a tub having a substantially semicylindrical bottom, an agitator including a bar, arms fixed to the ends of the bar, means pivotally mounting the arms for oscillation about the axis of said semicylindrical bottom, flexible wings diverging from opposite edges of the bar in the direction of said bottom, and means carried by said arms for supportingly retaining the wings from scraping contact with the 45 bottom of the tub.

3. In a washing machine, a tub having a substantially semicylindrical bottom, an agitator including a bar, arms fixed to the ends of the bar, means pivotally mounting the arms for oscillation 50 about the axis of said semicylindrical bottom, perforate flexible wings diverging from opposite edges of the bar in the direction of said bottom, and means carried by said arms for supportingly retaining the wings from scraping contact 55 with the bottom of the tub.

4. In a washing machine, a tub having a substantially semicylindrical bottom, an agitator including a bar, arms fixed to the ends of the bar, means pivotally mounting the arms for oscillation 60 about the axis of said semicylindrical bottom, flexible wings diverging from opposite edges of the bar in the direction of said bottom, and means carried by said arms for supportingly retaining the wings from scraping contact with the bottom of the tub, said wings having sufficient yieldability away from said retaining means to prevent wedging of articles under the agitator.

5. In a washing machine, a tub having a substantially semicylindrical bottom, an agitator including a bar, arms fixed to the ends of the bar, means pivotally mounting the arms for oscillation about the axis of said semicylindrical bottom, perforate flexible wings diverging from op- 75

posite edges of the bar in the direction of said bottom, and means carried by said arms for supportingly retaining the wings from scraping contact with the bottom of the tub, said wings having sufficient yieldability away from said retaining means to prevent wedging of articles under the agitator.

6. In a washing machine, a tub having a substantially semicylindrical bottom, an agitator including a bar, flexible arms fixed to the ends of the bar and having inwardly extending stops spaced below the bar, flexible agitator wings fixed to the bar and having portions engaging the stops, and means pivotally mounting the arms for oscillation about the axis of said semicylindrical bot-

tom with the flexible wings in slightly spaced relation with said bottom.

7. In a washing machine, a tub having a substantially semicylindrical bottom, an agitator including an inverted T-shaped bar, arms fixed to the ends of the bar, means pivotally mounting the arms for oscillation about the axis of said semicylindrical bottom and with the head flange of said bar supported in spaced relation with said bottom, flexible wings diverging from opposite edges of said head flange in the direction of said bottom, and means carried by said arms for supportingly retaining the wings from scraping contact with the bottom of the tub.
